UNITED STATES PATENT OFFICE.

JOHN BRODNER, OF SEATTLE, WASHINGTON.

AUTOMATIC FEEDER.

Application filed May 31, 1921. Serial No. 473,987.

To all whom it may concern:

Be it known that I, JOHN BRODNER, a citizen of the United States, residing at Seattle, in the county of King and State of Washington, have invented a certain new and useful Improvement in Automatic Feeders, of which the following is a specification.

My invention relates to improvements in automatic feeders and the object of my invention is to provide a feeder adapted to automatically feed chickens or other fowls at any desired and predetermined time.

Another object is to provide an automatic feeder embodying novel closure means adapted to be automatically actuated by a suitable timing mechanism.

A further object is to provide an automatic feeder embodying novel centrifugal or distributing means adapted to be automatically actuated by the falling feed to thus distribute the same over a large area.

A still further object is to provide an automatic feeder embodying simplicity, durability and economy in construction, that is positive and efficient in operation and that will not readily get out of order.

With the above and other objects in view which will appear as the description proceeds, my invention resides in the novel construction, combination, adaptation and arrangement of parts hereinafter described and claimed.

I accomplish these objects by devices illustrated in the accompanying drawings where-

in—

Figure 1 is a view in rear end elevation of an automatic feeder embodying the features of my invention, part of the door of the feeder being broken away to more clearly illustrate the position of the timing mechanism.

Fig. 2 is a view in vertical longitudinal section of the same taken on a broken line 2, 2 of Fig. 1.

Fig. 3 is a top plan view of the centrifugal member adapted for use with my device as it would appear when removed from the same, and

Fig. 4 is a view in horizontal section of my feeder taken on a broken line 4, 4 of Fig. 2.

Referring to the drawings, throughout which like reference numerals designate like parts, the numeral 10 designates my automatic feeder, which comprises a casing 11, a supporting bail 12, a removable bottom 13, a

ball valve or closure 14, a cord 15, a drum 16, a timing or clock mechanism 17, a stop 18, a suspension or hanger member 19 and a centrifugal or distributing member 20.

The casing 11 is adapted to be normally disposed in a vertical plane and is formed substantially rectangular in cross-section, being provided substantially midway of its height, thereby with a transversely disposed horizontal wall 21, to thereby form a lower compartment 22 for the reception and storage of the feed or grain and an upper compartment 23 adapted to receive the timing mechanism 18.

The supporting bail 12 is adapted to be pivotally secured or attached at its lower ends 24 to the upper ends of the side walls of the casing 11 in any well known manner, and in medial relation with respect to the said walls.

The removable bottom 13 is adapted to serve as a closure for the lower end of the lower compartment 22, the said bottom 13 having downwardly converting walls 25 which terminate in a circular discharge aperture 26 formed on the lower end of said bottom 13.

To properly support the bottom 13 in its normally operative position within the casing 11 I have provided the walls of the casing 11 contiguous to their lower ends with inwardly and downwardly convergent flanges or lips 27, on which the bottom 13 is adapted to normally rest as shown in Fig. 2.

The ball valve 14 is adapted to normally seat in the lower end of the bottom 13, to thus serve as a closure for the discharge aperture 26 formed in said bottom 13.

The cord 15 is adapted to be fixedly secured at its lower end to the ball valve 14, while at its upper end it is adapted to pass through an opening 28 formed in the horizontal wall 21 and thence upwardly over the drum 16 to be attached thereto, in any well known manner.

The drum 16 is adapted to be mounted upon and fixedly secured to an arbor 29 of the timing mechanism 17, which timing mechanism may be formed from any well known type of alarm clock. The arbor 29 of said timing mechanism is normally the winding stem of the alarm mechanism of said alarm clock.

In practice I dispose the timing mechanism 17 within the upper compartment 23

adjacent the forward end and to one side of the same, as shown more clearly in the drawings, to thus bring the cord 15 in vertical central alignment with the discharge aperture 26.

To facilitate and expedite the setting of the timing mechanism 17, I have provided the forward wall of the upper compartment 23 with an opening 30, which opening is 10 adapted to coincide and register with the dial portion of said time mechanism.

To further facilitate and expedite the setting of the timing mechanism and to render said mechanism readily accessible for winding 15 the several mechanisms thereof, I have provided the rear wall of the upper compartment 23 with a door 31, which door is adapted to be hingedly mounted at 32 to said rear wall of said upper compartment.

20 The stop 18 is adapted to be fixedly secured upon the cord 15 below and in spaced relation to the horizontal wall 21 of the casing 11, as more clearly shown in Fig. 2.

To facilitate and expedite the filling or 25 replenishing of the lower compartment 22 with the desired feed or grain, I have formed and provided in the horizontal wall 21 of the casing 11 a rectangular opening 33, which opening is medially disposed in said horizontal wall adjacent the rear end thereof, as shown more clearly in Fig. 4.

The suspension or hanger member 19 is 30 adapted to be suspended from the lower end of the casing 11. The said member comprising downwardly divergent portions 34 and upwardly bent convergent portions 35 all of which may be formed integral from a round rod, as shown in the drawings.

40 The upper ends 36 of the downwardly divergent portions 34 are adapted to be pivotally secured in the forward and rear walls of the casing 11 adjacent the lower ends thereof and in medial relation thereto, as shown in Fig. 1.

45 The upwardly convergent portions 35 are bent to extend upwardly at a slightly lesser angle than the angular disposition of the downwardly divergent portion 34, and are adapted to be joined or bent at a point substantially midway of the height of said divergent portions 34. Said convergent portions 35 are provided at their juncture with a concavity 37.

The centrifugal or distributing member 20 50 is formed in the shape of a hollow cone and is adapted to be operatively disposed for rotation upon the suspension member 19 in axial alignment with the aperture 26.

To minimize or eliminate friction between 60 the centrifugal member 20 and the suspension member 19, I have provided said centrifugal member 20 with a ball bearing 38, which ball bearing 38 is adapted to be secured within the member 20 adjacent the apex thereof and to normally seat in the con-

cavity 37 formed in the suspension member 19, when the centrifugal member 20 is operatively disposed thereon.

To positively insure of the proper rotation of the centrifugal member 20, I have 70 provided the conical or peripheral walls of said member with a series or a plurality of spaced vanes or blades 39, which vanes may be formed by cutting angular portions in said conical walls and bending said angularly cut portions upwardly and outwardly to 75 the desired angle or curve.

To positively insure of the proper and wide distribution of the feed or grain over a large area, I have provided the centrifugal 80 member 20 at its base or periphery with an outwardly projecting annular flange 40, on which said feed or grain is adapted to strike or impinge and be deflected therefrom during the operation of my automatic 85 feeder.

In the operation of my automatic feeder with the several elements comprising my device in their proper operative position as 90 illustrated in Fig. 2, the operator or attendant fills the compartment 23 with the desired feed or grain, he then winds the clock mechanism and sets the alarm mechanism for the time he wishes the feeder to 95 actuate and suspends the feeder in any desired position within the chicken coop.

The alarm mechanism of the clock 17 will then be actuated in a well known manner at the desired or designated time thereby 100 rotating the drum 16 and winding the cord 100 15 thereon to thus raise the ball valve 14 from the aperture 26, whereupon the feed or grain stored within the compartment 22 will be discharged from said compartment 105 and flow through the aperture 26, to thus fall or drop on the centrifugal member 20 to thereby rotate the same by striking or impinging the vanes 39 of said member.

In practice and after exhaustive experimentation, I have found it convenient and 110 advisable to form and provide the member 20 with an upper and lower set of vanes to thus greatly increase the action of the falling feed or grain, as said grain after striking or impinging the upper series of vanes 115 will be deflected therefrom to strike the lower set of vanes, when it will be again deflected to strike the annular flange 40 from whence it is deflected to the ground or floor.

It will be readily apparent by referring to 120 the drawings that the force derived from the falling or dropping grain may be also increased by spacing the member 20 at a greater distance from the aperture 26 to thus utilize to a greater degree the force of 125 gravitation.

It will also be apparent from the foregoing 130 that the force or energy of the falling grain is greatest when the ball valve 14 opens the aperture 26 and that said force

gradually and uniformly decreases as the grain is discharged from the compartment 22, thus causing the centrifugal member 20 to be rotated at its highest speed during the initial discharge of said grain, to thus throw the same to the maximum distance to thereby cover the maximum area, which distance or area is gradually and uniformly decreased as said grain is discharged and the member 20 slows down.

It will therefore be obvious that the foregoing action is productive of the maximum and desired results as the feed or grain is thus uniformly and evenly distributed over a considerable area.

The stop 18 on the cord 15 is adapted to normally abut the horizontal wall 21 when the valve 14 is in an open position, to thus limit the travel of said valve as will be obvious.

If desired the distributing member 20 may be fixedly secured in an operative position upon the suspension member 19, in which event the falling grain strikes or impinges said distributing member 20 and is deflected therefrom without rotating same.

From the foregoing description taken in connection with the accompanying drawings, the advantages of the construction and the method of operation of my automatic feeder will be readily apparent to those skilled in the art to which my invention pertains, to thus enable those so skilled to construct and operate the same, but, while I have shown and described the construction and operation of an automatic feeder embodying the

features and principles of my invention, which I now consider to be the best embodiment thereof, I desire to have it understood that the automatic feeder shown is merely illustrative and that such changes may be made when desired as are within the scope of my invention and embodied in the accompanying claims.

What I claim is:

1. An automatic feeder comprising a storage container, means for automatically discharging the feed from the container, a feed distributor suspended beneath the container, the distributor and mounting thereof embodying a wire frame having outer side bars diverging downwardly, and a central inverted V-shaped frame portion having the apex vertically alined with the discharging means and said distributor embodying a conical shell.

2. An automatic feeder comprising a storage container, means for automatically discharging the feed from the container, a wire frame bent intermediate the ends thereof to provide a central inverted V-shaped portion, with the free ends of the wire frame freely mounted in the opposite side walls of the container adjacent the lower end thereof, a ball bearing supported at the upper end of the inverted V-shaped portion, and a cone-shaped deflector rotatably supported on the ball bearing of the inverted V-shaped frame.

In witness whereof, I hereunto subscribe my name this 26th day of May A. D. 1921.

JOHN BRODNER.
